UNITED STATES PATENT OFFICE.

HANS LOUIS JENSEN, OF DAYTON, OHIO, ASSIGNOR TO THE EGRY REGISTER COMPANY,
OF DAYTON, OHIO, A CORPORATION OF OHIO.

PRINTING-PRESS.

1,062,917.

Specification of Letters Patent.

Patented May 27, 1913.

Application filed January 2, 1912. Serial No. 668,868.

To all whom it may concern:

Be it known that I, HANS LOUIS JENSEN, a citizen of the United States, residing at Dayton, in the county of Montgomery and State of Ohio, have invented certain new and useful Improvements in Printing-Presses, of which the following is a specification, reference being had therein to the accompanying drawing.

10 This invention relates to printing presses and more particularly to printing presses designed for printing bills or other forms, the production of which requires a series of printing operations. For example a bill of lading requires four separate printing operations, it is printed on both sides, the successive bills are consecutively numbered and a red ink number is printed on the face of the bill to indicate whether it is an original, second or third copy. In addition the bills are punched to form therein the desired apertures. As now constructed many of the machines which will produce these bills are very large and not only occupy much valuable floor space but are very expensive. Moreover, the arrangement of the usual machine is such that the printing rolls and the coöperating parts are not readily accessible, the setting up of the machine or its preparation for printing a given form being rendered very difficult.

15 The object of the present invention is to provide a press to produce forms or bills requiring a series of printing operations which will be very compactly arranged so that it will occupy a relatively small amount of space; and which will have its printing rolls so arranged that they will be readily accessible and of such a construction that 20 the plates can be quickly and easily attached to and removed from the same, thereby enabling the machine to be quickly and easily set up for a particular piece of work.

25 In the accompanying drawings, Figure 1 is a section taken just inside one of the frame members and showing the gearing carried by both frame members in dotted lines; Fig. 2 is an elevation of the printing roller showing the means for attaching the 30 plates thereto in section; Fig. 3 is an end view of the same; Fig. 4 is an end view of the lower section thereof; and Fig. 5 is an end view of the upper section thereof.

35 In these drawings I have illustrated one embodiment of my invention and have shown

the same as comprising a frame formed of two upright members 1, only one of which is illustrated in the drawings, the other frame member being a duplicate of that here shown. The frame is of a relatively great height and, in the present instance, its height is considerably greater than its length. At its front and rear ends the frame is provided with supporting devices for paper rolls, that device at the rear end of the frame being adapted to support the supply roll from which the paper is fed to the press and the device at the front end of the machine being adapted to support a rewinding roll upon which the printed forms are wound. While these supporting devices may be of any suitable character I have shown each as comprising a pair of arms 2 mounted on a transverse shaft 3 mounted in the side members of the frame. Each of the arms 2 of each device, of which but one is here shown, is provided at its free end with a half bearing 4 adapted to receive the end of the supporting shaft 5 for the paper roll 6. Mounted upon the frame in a fixed position are segmental bearings 7 arranged to coöperate with the half bearings 4 of the arms to retain the rolls in position when the arms 2 are in their upright position. A lever 8 is rigidly secured to the shaft 3 and by manipulating this lever the arms 2 can be lowered into a substantially horizontal position and the roll of paper rolled between the arms with the projecting ends of the shaft in a position to be engaged by the half bearings when the arms are elevated, thus causing the elevation of the arms to lift the roll into its proper position, as shown in the drawings.

40 In order to arrange the mechanism as compactly as possible and at the same time have the parts thereof readily accessible I have arranged the mechanisms which act upon the paper about the edge of the frame, and the paper as it is guided through the several mechanisms from the supply roll to the rewinding roll travels in approximately an inverted U-shape path. The present device comprises three rotary printing couples, each comprising a printing roll and a 45 platen. Two of these printing couples are arranged near the front and rear ends of the frame, respectively, are mounted in such positions that the paper will pass between the two members of the respective couples in an up- 50

ward and downward direction, respectively, and are so arranged that the printing roller is readily accessible. A third printing couple is arranged near the top of the frame and is so mounted that the paper will pass between the two members of the couple in a substantially horizontal plane. The first printing couple which is arranged near the rear edge of the frame comprises a printing roll 9 and a platen 10 mounted on shafts 11 and 12, respectively, which, in turn, are mounted in bearings formed in the frame near the edge thereof. The axes of the two members of the couple are arranged transversely to the height of the machine but at an inclination to the vertical. This arrangement permits the paper to pass upwardly between the two members of the couple and at the same time supports the printing roll which, in the present arrangement, is the upper roll, in such a position that it is readily accessible to the operator. One of the rolls is movable relatively to the other to throw off the impression, and, in the present instance, the platen is mounted in an eccentric bearing 13 which permits it to be moved away from the printing or form roll. The inking mechanism for the form roll is of a known character and is indicated as a whole by the reference numeral 14. The paper is guided from the supply roll between the two members of the printing couple by passing the same first about guide rollers or drums 15, thence about a guide 16, thence between the two members of the couple and about a guide 17 from which it extends upward about another guide 18 carried by the inking mechanism, thence to the second couple which is similar in construction to that just described and comprises a platen 19 and a printing roller 20 arranged to print on the opposite side of the web from that printed upon by the printing roll 9. The axes of the two members of this rotary couple are arranged in an approximately vertical plane so that the paper will pass between the same in a transverse direction. The plane of the axes of the two members lies between the paper roll supporting devices and the printing couples which are arranged above the same and thus allows the parts to be compactly arranged. The third printing couple comprises a platen 21 and a printing roll 22. This latter roll, however, is not the ordinary form roll but has mounted thereon a series of numbering devices adapted to print consecutive numbers upon the successive bills or forms as they pass between the two members of the printing couple. The detail construction of this numbering device is not a part of the present invention and is, therefore, not here described in detail, it being sufficient for the purpose of the present invention to state that the two members of the couple are rotary and in their broad

aspects are similar to the rotary members of the other printing couples. The inking devices for the second and third printing couples, which are indicated at 23 and 24, respectively, are of ordinary construction and require no description in connection with the present invention. A punching device comprising two rotary members 25 and 26 adapted to form the desired perforations in the bills, is mounted in the frame between the third printing couple and the rewinding roll 6. Here again the detail construction of the punching devices is not a part of the invention and is not here described, it being sufficient to state that these punching devices comprise two members rotatable about parallel axes.

The several operating devices may be driven in any suitable manner but preferably by trains of gearing mounted upon the two side members of the frame and connecting the several moving parts with a suitable source of power.

It will be noted from the foregoing description that the printing rolls 9, 20 and 22 are arranged in such positions that they are readily accessible from the exterior of the machine. To further facilitate the setting up of the rolls 9 and 20, that is, the applying thereto of the printing plates, I have so constructed these rolls that the plates can be quickly and easily clamped thereto. To this end I have divided each roll longitudinally to form two sections, the lower section being here indicated by the reference numeral 27 and the upper section by the reference numeral 28. The lower section is mounted on the shaft, which, in the case of the first couple, is indicated by the reference 11 and the upper section 28 is movably connected to the lower section. Preferably this connection is a hinged one and is formed by a longitudinal hinge pin 29 extending through apertured lugs on adjacent portions of the respective sections of the roll.

The two sections of the roll may be moved relatively one to the other in any suitable manner to expand and contract the roll. In the present instance I have shown a link 30 mounted on a stud 31 rigidly secured to one end of the upper section 28 and extending across the adjacent surfaces of the two sections of the roll and mounted upon an eccentric pin 32 carried by a stud 33 journaled in the lower section 27 of the roll. The pin 32 is provided on its outer end with a squared head 34 adapted to receive a wrench to enable the stud to be rotated. It will be apparent that the rotation of the stud will cause the eccentric pin to move relatively to the upper section of the roll and, consequently, the link will be actuated to move the upper section relatively to the lower section. In order that the parts may be locked in their adjusted positions I have provided

the link 30 with an extension extending beyond the stud 33 and having therein a slot 35 to receive a cap screw 36 which extends into the end of the roll and by means of 5 which the link can be locked against movement relatively to the lower section of the roll, thereby locking the two sections in their adjusted positions. Suitable clamping members are mounted on the exterior of the roll 10 and coöperate therewith to hold the plates in position thereon. In the present instance these clamping members comprise rings 37 extending about the roll and having oppositely extending flanges 38 adapted to extend over lips or projections 39 formed on the ends of the plates, which are shown at 15 40. The arrangement of the two sections of the roll is such that when in their expanded positions they will form a substantially true 20 cylinder and conform to the inner circumference of the plates. The clamping rings 37 are of such a size that when the sections have been expanded into substantially true 25 cylindrical form the projections 39 of the plates will be held firmly between the flanges on the clamping rings and the body of the roll, thus quickly and easily securing the same in position. It will be understood that 30 the plates are formed of substantially semi-cylindrical form and are placed in position on the form and the clamping rings slipped over the projections on the ends thereof. The fit of the parts is sufficiently close to retain each plate temporarily in position. 35 The next adjacent plate is then slipped into position on the other side of the ring and another clamping ring applied to the opposite end until all the plates are in position. The roll is then expanded and the several plates 40 clamped in place, all of which can be done very quickly and easily. This mechanism combined with the readily accessible positions of the form rolls enables the forms to be quickly and easily applied and adjusted 45 on the rolls and results in a great saving of time and labor over the system now commonly in use.

The operation of the device will be readily understood from the foregoing description and it will be apparent that the machine which I have produced is of a very compact arrangement, the parts being mounted in such a manner that the organized machine occupies but a small amount of space; and 50 further that the several parts are readily accessible from the exterior of the machine and are of such a character that they can be

quickly and easily manipulated to prepare the machine for operation.

While I have shown and described one 60 embodiment of my invention it will be understood that this has been chosen for the purpose of illustration only and that I do not desire to be limited to the details of construction shown and described, for obvious 65 modifications will occur to a person skilled in the art.

Having thus fully described my invention, what I claim as new and desire to secure by Letters Patent, is:—

1. A printing roll comprising a plurality of longitudinal sections movably connected one to the other, means for moving one of said sections relatively to the other, and clamping rings extending about the exterior 75 of said sections and adapted to engage the printing plates, whereby said plates may be clamped to said roll.

2. A printing roll comprising two longitudinal sections pivotally connected one to the other, a link pivotally connected to one of said sections, a pin eccentrically mounted in the other of said sections and extending through said link, whereby the rotation of said pin will move one of said members 80 toward or away from the other, clamping rings extending about the exterior of said sections and adapted to extend over the edges of the printing plates, whereby the expansion of said sections will cause said 85 plates to be clamped between the sections and the rings.

3. A printing roll comprising two longitudinal sections pivotally connected one to the other, a link pivotally connected to one 95 of said sections, a pin eccentrically mounted in the other of said sections and extending through said link, whereby the rotation of said pin will move one of said members toward or away from the other, and means 100 for locking said sections in adjusted positions, clamping rings extending about the exterior of said sections and adapted to extend over the edges of the printing plates; whereby the expansion of said sections will 105 cause said plates to be clamped between the sections and the rings.

In testimony whereof, I affix my signature in presence of two witnesses.

HANS LOUIS JENSEN.
